UNITED STATES PATENT OFFICE.

DELL W. MITCHELL AND FRANK JEWELL, OF POMONA, CALIFORNIA.

WORKING-GARMENT.

1,087,037.

Specification of Letters Patent.

Patented Feb. 10, 1914.

Application filed February 27, 1913. Serial No. 751,125.

To all whom it may concern:

Be it known that we, DELL W. MITCHELL and FRANK JEWELL, citizens of the United States, residing at Pomona, in the county of Los Angeles and State of California, have invented certain new and useful Improvements in Working-Garments, of which the following is a specification.

Our invention relates to that class of garments worn by operators in mills and factories, carpenters, painters, mechanics and artisans in general, and is also designed as a boy's garment, and has for its object the providing of a simple, economical and efficient garment in which the trousers, shirt and jacket are formed in one piece; and the invention consists in the features, combinations and details of construction hereinafter described and claimed.

In the accompanying drawings:—Figure 1 is a front view of the combination overalls and jumper, showing the garment as it will appear when in use. Fig. 2 is a rear view of the same, Fig. 3 is a rear view with the suspenders unfastened and flap depending, Fig. 4 is a side elevation of the garment, Fig. 5 is a detail elevation of the extension placket for increasing the size of the garment at the waist and breast, Fig. 6 is an elevation of the front open about half way above the crotch with the flap concealing the buttons.

In the art to which this invention relates it is well known that garments are constructed with the trousers in one portion and the jacket or jumper in another portion. This is objectionable in that when it is necessary to put on or take off the garment it must be taken off piecemeal and does not protect the operator from dirt or make as efficient a garment as might be desired. It also requires more time to put on or take off the two pieces than our one piece garment.

Our improvement relating to the extension at the waist allows the garment to be expanded sufficient to make it suitable and easy to wear by a person of larger girth, and when expanded or extended leaves the garment without wrinkles or puckers, giving a neat appearance, as though the garment had been originally made the maximum size.

Another improvement is the manner and means by which the length of the garment may be shortened by the suspenders which allow a reduction in the length without

puckering or drawing the garment. The neat appearance of the garment after having been shortened in length and increased in girth, thereby changing the sizes in two ways, constitutes one of the improvements which we claim to be a distinct advantage over any other garment of this character.

Referring more particularly to the drawings for a detail description of our invention, 1 designates a medial opening extending longitudinally from the neck to the crotch, the dotted lines showing the flap with the buttons concealed. An opening of this length makes the garment easy to put on or take off.

D, D, are set-in pockets as in ordinary garments, and V is a pocket with two divisions, one for a watch and one for a pencil.

C, C, are the sleeves buttoned at M; F, F, are the suspenders buckled at G; and N, N, are eyelets in the suspenders whereby the length of the garment may be decreased as described.

Dotted lines L, L, indicate the increased waist size that may be given to the garment by opening the placket P, as shown in Fig. 5.

Fig. 2 shows the back of the garment with the pockets E, E, suspenders F, F, the placket P, P, buttoned up and the dotted lines L, L, showing the extension, same as Fig. 1. It will be noticed in this drawing that the bottom of the jumper as shown by dotted line T, extends down sufficiently so that the flap, to which the suspenders are attached, will cover amply, when the garment is in use. The dotted lines U, U, at the junction of suspenders and flap indicate the reinforcement at this point to give increased strength.

It might be stated here that all seams are reinforced and strength given wherever necessary to make a substantial and durable garment.

Fig. 3 shows the flap S, and the suspenders F, let down. The dotted lines I show the back of the seam down the front of the garment. This drawing indicates the openness of the garment when it is desired to put it on or take it off. With the flap down and the jumper or blouse part of the garment unbuttoned at the sides, it leaves the most of the garment from the hips to nearly the arm pits open, thereby making it very easy to put on or take off. And also, leaving the blouse or jumper unbuttoned, and the suspenders buckled in place, there is ample

2
room to insert the hand under the jumper or blouse to reach any part of the upper portion of the body.

Fig. 4 giving a side view is particularly intended to show the placket P, Fig. 5, buttoned up, and the length of the opening which is obtained when the flap and jumper or blouse are unbuttoned. The dotted lines L, L again indicate the increased size which may be given to the garment when the placket P is opened.

Fig. 5 shows the placket P opened. J, J, are concealed fasteners to keep the placket in place, closed, if it is not desired to use the increased size. K, K, are the buttons that fasten this portion of the garment.

Fig. 6 shows the front of the garment partly open so as to show the buttons and button holes concealed. If the drawing had shown the whole front open, the opening would have shown down to the crotch.

The manner in which the flap is made and the way the buttons and button holes are used make the front of the garment proof against dust and dirt entering underneath the front.

Having thus described our invention, what

we claim as new and desire to secure by Letters Patent, is:—

1. A one-piece garment comprising a jacket and a trousers portion, a placket arranged upon opposite sides of the waistline and extending longitudinally into the trousers and jacket, fastenings for said plackets, and suspenders connected at one end to the rear portion of the garment, and at the other end to the upper front portion of the jacket.

2. A one-piece garment comprising a jacket and a trousers portion, said garment having a rear opening in the plane of the waistline, a flap adapted to cover said opening, a placket arranged at each end of the opening and extending longitudinally into the trousers and jacket, fastenings for said flap and the plackets, and suspenders connected at one end to the flap and at the other end to the upper front portion of the jacket.

In testimony whereof we hereunto affix our signatures in presence of two witnesses.

DELL W. MITCHELL.
FRANK JEWELL.
